PUMP ROD ADJUSTING DEVICE

John Robert Lee Carl, Corsicana, Tex., assignor of one-third to Newman C. Thornton, Mexia, and one-third to Percy Ledwell, Corsicana, Tex.

Application October 11, 1957, Serial No. 689,548

6 Claims. (Cl. 74—108)

This invention relates to new and useful improvements in devices for adjusting the length of well pump rods.

One object of the invention is to provide an improved device for adjusting the length of well pump rods which is of such construction that the effective length of the rods may be readily varied with minimum effort and with minimum danger of damaging the equipment or injuring the operator.

Another object of the invention is to provide an improved adjusting device for well pump rods which is so constructed that it may be readily mounted on and removed from the polished rod of a well pump whereby the device may be used on a plurality of well pumps and need not be permanently mounted.

A further object of the invention is to provide an improved pump rod adjusting device having means for connection with the crosshead which suspends the polished rod from the walking beam of a pumping unit and means for connection with the polished rod together with means for moving the device toward and away from the crosshead to vary the point of connection of said crosshead to said rod and thereby increase or decrease the effective length of said rod.

A particular object of the invention is to provide an improved pump rod adjusting device, of the character described, which includes an auxiliary member adapted to be suspended from the crosshead of the pumping unit by adjustable elements and having means for adjusting the length of the elements to move the auxiliary member relative to said crosshead.

A construction designed to carry out the invention will be hereinafter described, together with other features of the invention.

The invention will be more readily understood from a reading of the following specification and by reference to the accompanying drawings, wherein an example of the invention is shown, and wherein:

Fig. 1 is an end elevational view of a portion of well pumping unit having mounted on its polished rod an adjusting device constructed in accordance with the invention,

Fig. 2 is a side elevational view of the unit,

Fig. 3 is a perspective view of the device showing its connection to the rod and crosshead of the unit,

Fig. 4 is an enlarged, perspective view of one of the adjustable elements of the device,

Fig. 5 is a side elevational view, partly in section, of the mounted device, and

Fig. 6 is a horizontal, cross-sectional view, taken on the line 6—6 of Fig. 5.

In the drawings, the numeral 10 designates a portion of a conventional well pumping unit which includes a pivotally mounted walking beam 11 having a horsehead 12 on one of its ends. A bridle 13, of the usual construction, is secured to the horsehead 12 for flexibly suspending a hanger bar or crosshead 14 which is adapted to support the usual string of pump rods. Only the uppermost or polished rod 15 is shown and extends

2

through the crosshead 14, being adjustably connected thereto by an overlying clamp 16. As is well known, due to this arrangement, the rod is reciprocated by the rocking of the beam 12 with minimum bending of said rod. It is frequently necessary to adjust the effective length or stroke of the pump rods and this is a difficult and dangerous task since it is necessary to support the weight of said rods during such adjustment. It is desirable to adjust the length without stopping operation of the pumping unit in order to conserve time and because of the elongation of the rods under load. In most instances, the length is increased so that the pump plunger or its traveling valve will strike the standing valve (none of which are shown) on its downstroke to provide a bumping or shaking action for loosening sand or other debris or releasing a gas lock which might hinder proper seating of the valves. This necessary adjustment is facilitated by the improved device of this invention.

The adjusting device includes an auxiliary crosshead 20 or member 17 in the form of a horizontal rectangular block, of greater length than width, having an underlying, complementary plate 18 secured thereto by recessed screws 19. An upright slot or groove 20 is formed in one side of the member medially of its ends for receiving the polished rod 15 (Figs. 3, 5 and 6). For receiving a pair of hanger elements 21, a pair of upright cylindrical bores or openings 22 extend through the block and plate on each side of the slot 20. Each element 21 includes a screw-threaded rod or stem 23 having an elongated, horizontal head 24 on its upper end whereby the element is substantially T-shaped (Fig. 4). An arcuate recess 25 is formed in the underside of one end portion of the head 24 to provide a hook 26 and a horizontal opening 27 extends transversely through the other end portion of said head for pivotal connection with the end link of a chain 28. As shown most clearly in Figs. 3 and 5, the chains 28 are adapted to be passed over the crosshead 14 and engaged with the hooks 26 to connect the hanger elements to said crosshead.

The threads of the hanger elements 21 are relatively coarse or of the worm type and mesh with the complementary screwthreaded bores 29 of a pair of pinions 30 which are mounted in recesses 31 formed in the contiguous surfaces of the block 17 and plate 18 (Fig. 6). Suitable bearings 32 overlie the pinions 30 to facilitate rotation thereof and reciprocal movement of the member relative to the hanger elements 21 (Fig. 5). For imparting rotation to the pinions, cylindrical shaft 33 extends through a complementary, horizontal bore or opening 34 which extends longitudinally of the member between its block and plate with the recesses 31. The shaft 33 has worm teeth 35 for meshing with the pinions and is of greater length than the bore 34 so as to project from each end thereof. A reduced, polygonal or square pin 36 is formed on each end of the shaft for engagement by a suitable tool, such as the crank 37 shown in dotted lines in Fig. 6. The medial portion of the bore and shaft between the recesses 31 and worm teeth 35 are reduced in diameter as shown by the numeral 38 to prevent endwise displacement of said shaft. A clamp 39, similar to the clamp 16 and including a pair of complementary sections 40 connected by suitable bolts and nuts 41 is adapted to be fastened to the polished rod 15 in overlying relation to the block 17 when the chains 28 are engaged with the crosshead 14.

The adjusting device is readily mounted on the polished rod 15 whenever desired by engaging the chains around the crosshead and positioning said rod within the slot 20. In order to shorten the effective length of the rod, the free end links of the chains 28 are connected to the hooks 26 of the head 24 and the shaft 33 rotated so as to position the block 17 and plate 18 of the member adjacent

the lower ends of the stems 23 of the hanger elements 21. The clamp 39 is then attached to the rod immediately above the block. Upon reverse rotation of the shaft, the pinions 30 are driven so as to travel upwardly of the stems and raise the block and plate. Due to the clamp 39, the rod is lifted relative to the crosshead 14 so as to position the clamp 16 in spaced relation thereto. It is noted that during this relative movement, the adjusting device functions as an auxiliary crosshead whereby the clamp 16 may be loosened as soon as the weight of the pump rods is supported by said device. After the effective length of the rod has been decreased sufficiently, the clamp 16 is tightened into engagement with said rod immediately above the crosshead whereby the weight of the rod is again supported by said crosshead and clamp. If desired, the adjusting device may now be removed or left mounted on the rod for future adjustments.

In order to increase the effective length of the rod, the shaft 33 is rotated so as to position the member adjacent the upper end of the hanger elements 21. With the 20 chains 28 engaged around the crosshead, the clamp 39 is tightened to permit loosening of the clamp 16. In order to facilitate loosening of the clamp, the rod may be lifted by upward movement of the member so as to disengage said clamp from the crosshead. Since the 25 weight of the pump rods is supported by the adjusting device upon loosening of the clamp 16, the rod may be lowered relative to the crosshead by downward movement of the member relative to the hanger elements 21. When the desired length is reached, the clamp 16 is tightened to return the load to the crosshead. In most instances, the effective length of the rod is increased for the pumping or shaking action and then decreased to its original length.

The foregoing description of the invention is explanatory thereof and various changes in the size, shape and materials, as well as in the details of the illustrated construction may be made, within the scope of the appended claims, without departing from the spirit of the invention.

What I claim and desire to secure by Letters Patent is:

1. A device for adjusting the effective length of the rod of a well pump having a beam, a crosshead slidably engaged with the rod and a clamp overlying the crosshead for suspending the rod including a member for slidable engagement with the rod, a clamp for mounting on the 45

rod in overlying engagement with the member, means for connecting said member to the crosshead, and gear means in said member having driving connections with the connecting means for reciprocating said member to move the same toward and away from the crosshead for raising and lowering the rod relative to the crosshead.

5 2. A rod adjusting device as set forth in claim 1 wherein the connecting means includes a hanger element extending through and mounted in the member.

3. A rod adjusting device as set forth in claim 2 wherein the connecting means includes flexible means for adjustably connecting the hanger element to the crosshead for suspending the member therefrom.

10 4. A rod adjusting device as set forth in claim 1 wherein the connecting means includes a pair of hanger elements having threaded portions mounted in and extending through the member, the gear means including pinions on the threaded portions and a worm shaft meshing with the pinions.

15 5. A device for adjusting the effective length of the rod of a well pump having a beam, a crosshead slidably engaged with the rod and a clamp overlying the crosshead for suspending the rod including a member having an opening for slidably receiving the rod below the crosshead, a clamp for mounting on the rod in overlying engagement with the member, a hanger element having connection with the crosshead for suspending said member therefrom, the hanger element having a threaded stem extending through and mounted in said member, and gear means in the housing having driving connection with the threaded stem for reciprocating said member to move the same relative to said element and toward and away from the crosshead for raising and lowering the rod relative to the crosshead.

20 6. A rod adjusting device as set forth in claim 5 wherein the gear means includes a pinion on the threaded stem of the hanger element and a worm meshing with the pinion.
